UNITED STATES PATENT OFFICE

91,329

DESIGN FOR A ONE PIECE SPORT DRESS OR SIMILAR ARTICLE

Gladys B. Redman, Greenwich, Conn.

Application May 16, 1933. Serial No. 48,133

Term of patent 3½ years

To all whom it may concern:

Be it known that I, GLADYS B. REDMAN, a citizen of the United States, residing at Greenwich, county of Fairfield, and State of Connecticut, have invented a new, original, and ornamental Design for a One Piece Sport Dress, or Similar Article, of which the following is a specification, reference being had to the accompanying drawing, forming part thereof.

The single figure is a perspective view of the one piece sport dress.

I claim:

The ornamental design for a one piece sport dress, or similar article, substantially as shown.

GLADYS B. REDMAN.
